WING TARGET APPARATUS

Louis C. Bauman, St. Joseph, Mo.

Application February 5, 1935, Serial No. 5,121
Renewed April 6, 1936

9 Claims. (Cl. 124—17)

My invention relates to a wing target apparatus.

The object of my invention is to provide, in a manner as hereinafter set forth, an apparatus of the class referred to including a target element of the wing type mounted upon a propelled or projectable carrier with the element so formed as to simulate a bird on the wing when the carrier is projected.

10 A further object of my invention is to provide, in a manner as hereinafter set forth, an apparatus of the class referred to including a projectable target element of the wing type which is so formed as to decrease its resistance to air 5 when projected upwardly and to cause it to balloon when descending, whereby its flutter is increased.

20 A further object of my invention is to provide, in a manner as hereinafter set forth, a wing target apparatus including a target structure propelled by the exploded charge of a blank cartridge, a holding element for normally and slidably supporting the target structure in the path of the products from the exploded charge, 25 with the holding element having means for firing the cartridge.

25 A further object of my invention is to provide, in a manner as hereinafter set forth, a wing target apparatus including the holding element, 30 as aforesaid, having means, when the target element is propelled, to shield the operator's hand from injury caused by the products of the exploded charge employed to propel the target element through the air.

35 A further object of my invention is to provide, in a manner as hereinafter set forth, an apparatus of the class referred to, including a target of the wing type capable of being contracted in its upward flight and extended on its descent.

40 To the above ends essentially and to others which may hereinafter appear, my invention consists of such parts and such combination of parts which fall within the scope of the invention as claimed.

45 In the drawing:

Figure 1 is a side elevation of the wing target apparatus,

Figure 2 is a top plan view of the target element,

50 Figure 3 is a perspective view of the target and its carrier element assembled relative to each other,

Figure 4 is a section on line 4—4, Figure 1, and

Figure 5 is a section on line 5—5, Figure 3.

55 The apparatus includes a holder element 6 in

the form of a pistol of suitable type for firing blank cartridges. The barrel 7 of the pistol has arranged thereon and in encompassing relation with respect thereto between its transverse median and its inner end, an axially apertured circular shield 8 formed at its outer edge with a forwardly directed right angularly disposed annular flange 9. The shield 8 is anchored to barrel 7 by the holdfast means 9' which is disposed at the inner side of the shield. The latter may be of any diameter desired.

The apparatus includes a wing like target element 10 formed of a pair of oppositely extending outer parts 11, 12 and an intermediate part 13. The element 10 is preferably formed of a length 15 of paper stock of the desired thickness, but it is to be understood that any suitable material may be employed.

The element 10 is formed with a forward and a rear edge 14, 15 respectively. The former is curved, extends in the same arc throughout and is of greater length than edge 15. The latter consists of a pair of oppositely disposed edge portions 16, 17 of ogee curvature merging into each other at the transverse median of element 10. The outer ends of the edge portions 16, 17 merge into the ends of the edge 14 whereby each end of element 10 is pointed as at 18, 19. The said pointed ends are arranged in alignment and rearwardly of the axis of said element 10.

The outer parts 11, 12 gradually increase in width from the pointed ends 18, 19 respectively to the intermediate part 13. The parts 11, 12 have their outer faces formed with oppositely extending diagonally disposed crimps 20, 21 extending from the intermediate part 13 to the points 18, 19 respectively. The outer parts 11, 12 having their inner faces scored which align and are coextensive with the crimps 20, 21 respectively. Only one of the scores is shown and is indicated at 22, Figure 5.

The intermediate part 13, at the intersection of its horizontal and transverse medians, is formed with an opening 24 disposed at the axis of the element 10. The part 13 is also formed with a pair of oppositely disposed slits or cuts 25, 26 of like form. Each slit or cut has a semi-circular intermediate portion 27 and a pair of spaced endwise opposed, oppositely extending straight portions 28, 29 opening at their inner ends in the ends of the portion 27. The outer end of the portions 28, 29 are closed. The said straight portions are disposed at right angles to the ends of portion 27. The portions 27 of the cuts 25, 26 are arranged on opposite sides of and

are spaced from opening 24. The outer ends of the portions 28, 29 terminate at the points of emergence of part 13 with the parts 11, 12.

That portion of the part 13 between the slits or 5 cuts 25, 26 forms an abutment 30 and the portions of part 13 outwardly adjacent the slits or cuts 25, 26 provide retainers 31, 32 respectively. The purpose of abutment 30 and retainers 31, 32 will be hereinafter referred to.

10 The apparatus includes a carrier element 33 for the element 10. Preferably the carrier will be set up from an exploded shot gun shell to reduce the cost to a minimum. The inner diameter of carrier 33 will be such as to readily permit it to be slidably mounted upon barrel 7. The carrier 15 33 has an open rear end 34 and a closed forward end 35. The forward end 35 of carrier 33 is formed with a laterally disposed annular flange 36. As the carrier 33 is set up from an exploded 20 shot gun shell, its end 35 is formed with an exploded cap 37. The carrier 33 is positioned against the inner face of abutment 30 of element 10 with the exploded cap 37 directly opposing the opening 24. The inner edges of the retainers 31, 25 32 of part 13 are then arranged to abut the outer periphery of the carrier 33 inwardly of the flange 36. When carrier 33 and element 10 are in the position just referred to, the abutment 30 is extended from the retainers 31, 32 whereby element 30 10 and carrier 33 are clamped together due to the position of the intermediate part of element 10 with respect to the forward end of the carrier 33.

The crimps and scores provide for the contraction of the element 10 when the latter is projected in flight and provide for the extending or expanding of element 10 when the latter is descending.

The element 10 and carrier or element 33 are projected together due to the clamping of one to the other in the manner aforesaid. The carrier 40 33, with element 10 clamped to the forward end thereof, is positioned on barrel 7 in a manner whereby its rear end will abut shield 8 and its closed forward end be disposed in the path of 45 travel of the products of the exploded cartridge fired by the pistol, whereby on the firing of the cartridge the elements 10 and 33 will be projected bodily together in the air. When the cartridge is fired, the shield 8 prevents the gases and 50 unburned powder from burning the hand of the operator, and also acts as a buffer to the escaping gases from the exploded cartridge and thereby increases the propelling power.

When element 10 is projected into the air it provides a target simulating a bird on the wing. The manner of setting up element 10 decreases resistance to the air when projected and provides for a ballooning effect on its descent to increase flutter thereof.

60 What I claim is:

1. A wing target apparatus comprising a holder element having a part for supporting a blank cartridge, a part for exploding the cartridge and a part for conducting off therefrom the products of the explosion, a hollow carrier element normally slidably mounted upon said conducting off part and having a closed forward end positioned in the path of and propelled by said products, a target element of wing like form, said carrier and target elements having coacting means for clamping the target element upon the outer end of the carrier element to provide for the target element being bodily carried by the carrier element on the propulsion of the latter, and a shield encompassing said conducting off part intermediate the ends

of the latter and abutting the inner end of the carrier element when the latter is mounted on the holder element.

2. In a wing target apparatus, a target element of wing like form, and a hollow propellable carrier element having a closed forward and an open rear end, said target element and carrier element having inherent coacting interengaging means for clamping the target element upon the forward end of the carrier element, the coacting means of the target element being disposed lengthwise of the latter. 10

3. In a wing target apparatus, a contractible and expandable target element of wing like form, and a hollow propellable carrier element having a closed forward end and an open rear end for the entrance of propelling means therefor, said target element and carrier element having inherent coacting interengaging parts for clamping the target element about the outer periphery of the 20 carrier element in proximity to the forward end of the latter.

4. In a wing target apparatus, a contractible and expandable elongated target element of wing like form, and a hollow propellable carrier element having a closed forward end an open rear end for the entrance of propelling means therefor, said target element and carrier element having inherent coacting interengaging means for clamping the target element upon the outer periphery of the carrier element, the coacting part of the target element being disposed centrally of and positioned adjacent to the lengthwise edges and to the sides of the lengthwise median of the target element. 30

5. In a wing target apparatus, a target element comprising a one-piece body of wing like form having a pair of oppositely disposed end parts and an intermediate part, said end parts gradually decreasing in width from their inner ends to their outer ends from said intermediate parts, said outer parts having pointed outer ends, and said intermediate part being formed with spaced opposed slits having curved intermediate portions, said curved portions being oppositely disposed, 40 and said slits forming said intermediate part with an abutment portion and a pair of retainer portions spaced from said abutment portion, said retainer portions and abutment portion being so formed for clamping said element upon a propellable carrier element for the target element. 45

6. In a wing target apparatus, a target element comprising a one-piece body of wing like form having a pair of oppositely disposed end parts and an intermediate part, said end parts gradually decreasing in width from their inner ends to their outer ends from said intermediate parts, said outer parts having pointed outer ends, and said intermediate part being formed with spaced opposed slits having curved intermediate portions, said curved portions being oppositely disposed, 60 said slits forming said intermediate part with an abutment portion and a pair of retainer portions spaced from said abutment portion, said retainer portions and abutment portion being so formed for clamping said element upon a propellable carrier element for the target element, and said end parts having their outer faces formed with oppositely extending diagonally disposed crimps lengthwise thereof and their inner faces 65 with oppositely extending diagonally disposed scores lengthwise thereof aligning with said crimps. 70

7. In a wing target apparatus, a target element comprising a one-piece body of wing like 75

form having a pair of oppositely disposed end parts and an intermediate part, said end parts gradually decreasing in width from their inner ends to their outer ends from said intermediate parts, said outer parts having pointed outer ends, and said intermediate part being formed with spaced opposed slits having curved intermediate portions, said curved portions being oppositely disposed, said slits forming said intermediate 10 part with an abutment portion and a pair of retainer portions spaced from said abutment portion, said retainer portions and abutment portion being so formed for clamping said element upon a propellable carrier element for the target 15 element, said end parts having their outer faces formed with oppositely extending diagonally disposed crimps lengthwise thereof and their inner faces with oppositely extending diagonally disposed scores lengthwise thereof aligning with said 20 crimps, and said body having a forward edge and an inner edge, said forward edge being curved and upon the same arc throughout, said inner edge being formed of a pair of oppositely disposed portions of ogee curvature merging into 25 each other at the transverse median of said

body, and said portions of ogee curvature having their outer ends merging into the ends of said forward edge.

8. In a wing target apparatus, a target element, and a propellable carrier element for said target element, said carrier element being laterally flanged at its forward end, and said target element having means for seating directly against the forward end of the target element and spaced means for engaging under said flange whereby 10 the target element is clamped to the forward end of the carrier element.

9. In a wing target apparatus, a target element, and a propellable carrier element for said target element, said carrier element being laterally flanged at its forward end, said target element having means for seating directly against the forward end of the target element and spaced means for engaging under said flange whereby 15 the target element is clamped to the forward end of the carrier element, and said target element having means disposed lengthwise thereof to provide for its contracting and expanding when moving upwardly and downwardly respectively.
